BUTTONHOLE ATTACHMENT FOR SEWING-MACHINES.

SPECIFICATION forming part of Letters Patent No. 678,397, dated July 16, 1901.

Application filed February 16, 1900. Serial No. 5,405. (No model.)

To all whom it may concern:

Be it known that we, WILLIAM H. HARGRAVES and JOHN SIDNEY HEILIG, of Allentown, and JACOB ROBERTS, of Catasauqua, 5 Lehigh county, Pennsylvania, have invented a new and useful Improvement in Buttonhole Attachments for Sewing-Machines, of which the following is a specification.

Our invention relates to certain improvements in a sewing-machine attachment adapted for sewing buttonholes and capable also of use for tacking pockets, crotches, or other seams, and relates especially to improvements upon the attachments described in United 15 States Letters Patent Nos. 549,538 and 549,539, dated November 12, 1895.

The improvements will be hereinafter fully described, and the novel features thereof set forth in the claims.

20 In the accompanying drawings, forming part of our specification, Figure 1 is a plan view of the attachment; Fig. 2, a side elevation thereof. Fig. 3 is a central longitudinal section. Fig. 4 is a horizontal section on the 25 plane of the line 4-4 of Fig. 3. Fig. 5 is a side view of a pitman and segmental pinion forming a part of the attachment. Fig. 6 is a plan view of a ring forming part of the clutch device. Fig. 7 is a plan view of a lever forming 30 part of the clutch device, and Fig. 8 is a view of a cam for imparting vibratory movement to the cloth-clamp plate.

Similar letters of reference indicate similar parts in the several views.

35 The frame or casing of the attachment comprises the bed *a* and the body portions *a'* and *a''*, which parts are made integral with or permanently secured to the bed portion *a*. The forward end of the casing *a'* is provided with 40 a pair of jaws *a''*, one of which is fitted with a jam-screw *a''* for clamping the attachment to the presser-foot bar of the sewing-machine. In the frame portion *a'* is journaled a shaft *b*, one end of which projects beyond the casing and has fixed thereto a ratchet-wheel *b'*. A lever *b''* is fulcrumed on the said shaft between the casing *a'* and the ratchet-wheel *b'* and has a pawl *b'''*, held by a spring *b''* in engagement with said ratchet-wheel. A flat-headed screw *b''* has engagement with the lever *b''*, and between the screw-head and said

lever is a washer *b''*, in which there is a groove to receive one end of the spring *b''*. The other end of the spring *b''* rests in the groove (shown in dotted lines, Fig. 2) in the top of 55 the pawl *b'''*. This arrangement obviates the drilling of a hole in the pawl, which weakens it, and the spring can be readily adjusted and replaced. The spring *b''* is formed of a piece of round spring-wire not bent in any 60 way to weaken it. Such spring is therefore of greater strength and durability than previous constructions. The resting of the spring *b''* in a groove in the top of the pawl is of advantage, as the spring is thereby prevented from being knocked or crushed out of place by the work or other means when the attachment is in operation.

The forward end of the lever *b''* passes through and has sliding connection with an 70 eye *b''* of a link. The other eye *b''* of said link is at right angles to the eye *b''* and is secured on the needle set screw or clamp of the needle-bar, the connection being such that the link oscillates when the needle-bar reciprocates. This means of connecting the lever *b''* with the reciprocating needle-bar is more durable and permits a greater movement to be given the said lever than in the former constructions, and hence thicker goods may be 80 sewed. As the needle-bar reciprocates an oscillating movement is imparted to the lever *b''*, which, through the pawl *b'''*, gives a rotary motion to the ratchet-wheel *b'*.

In order to impart the desired vibratory 85 movement of the cloth-clamp plate, a cam-wheel *c* is held rigidly on the shaft *b* in any suitable manner, as by a set-screw *c''*. This wheel has a peripheral zigzag cam-groove *c'*, which is engaged from below by a roller *c''* 90 on a stud formed integral with a lever *c''*. This lever is fulcrumed on a screw-bolt *c''*, extending through an opening in the frame portion *a'*, and has its lower end reduced with respect to the body portion and screw-threaded to engage the lever *c''*. The screw-threaded portion of the bolt *c''* is also engaged by a nut *c''*, which is screwed up tightly against the lever *c''*. The nut *c''* not only serves to hold the retaining-plate *e* in position, but it 100 holds the lever *c''* firmly to the bolt *c''* under the rapid vibratory movement of said lever.

The nut c^6 works through a transverse slot c^2 in the retaining-plate e , such slot being of sufficient length to afford a clearance for the nut c^6 under the vibratory movement of the plate e . On the lever c^4 and having dovetailed engagement therewith is a cross-head slide d , which may be clamped to said lever in any desired position by a set-screw d' , which works through a longitudinal slot e' in the retaining-plate e .

The cloth-clamp f is rigidly secured to the forward end of a longitudinal slotted slide-plate f' , which plate is held in position between the bed-plate a of the frame and the retaining-plate e by means of the screws d' , c^6 , and p^4 . The slot f^2 of the cloth-clamp plate f' extends nearly the entire length of said plate and is engaged by the cross-head d , said slot being of sufficient width to allow clearance for the nut c^6 under the vibratory movement of the plate f' . In order to provide a better wearing-surface, shoes d^2 are inserted between the cross-head d and the inside walls of the slot f^2 . These shoes conform on their inner sides to the head d , and the outer sides are grooved to engage the walls of the slot f^2 , so that when placed in position said shoes will be held between the cross-head d and the walls of the slot f^2 . These shoes d^2 provide an excellent wearing-surface, and they may easily be replaced when worn out. It is obvious from the above that by the rotary motion of cam c lever c^4 will be vibrated in a horizontal plane and will impart a similar motion to the cloth-clamp f . The extent of throw or amplitude of vibratory movement of the cloth-clamp may be made greater or less by increasing or decreasing the distance of the cross-head d from the fulcrum c^5 .

We will now describe the means for imparting the desired longitudinal movement to the cloth-clamp slide necessary for the sewing of the side or binding stitches of a buttonhole. On the end of the shaft k in the frame portion a^2 is mounted a friction-clutch device for imparting a progressive rotary movement to said shaft. This clutch mechanism comprises a lever h , provided with a central opening adapted to fit over the shaft k , with some clearance between the two said parts, and a disk g^4 , having screw connections with the projecting end of the shaft k or otherwise securely attached to said shaft. The lever h is mounted on the shaft k between the disk g^4 and the frame of the attachment. In an annular groove g^8 on the inner side of the disk g^4 is placed a clutch-ring, formed of halves g^9 , each of said halves having a portion of one end removed, so as to leave a rectangular opening formed by the ends of the halves of the ring and the walls of the groove. In the opening thus formed a stud h' on the lever h fits snugly. The said lever has a portion of its periphery cut away, as shown at h^2 , one end of said opening being formed to provide a seat for a pin i' on a lever i and the

other end of said opening formed so as to engage one end of a spring h^4 , screwed to the frame portion a^2 . To operate the lever h , we provide a slide-bar i , which rests loosely upon a flange a^4 of the frame of the attachment, said slide-bar having a pin i' to engage the lever h , as above stated. The forward end of the slide-bar i is provided with a pin i^2 , which engages the end of lever b^2 , so that on the upward movement of the needle-bar the slide-bar i will rotate the lever h , giving the stud h' a twisting motion between the ends of the halves g^9 of the clutch-ring and jamming said halves against the outside wall of the annular groove g^8 of the disk g^4 , thereby locking together the disk g^4 , the ring formed of the halves g^9 , and the lever h , thus giving a rotary movement to the shaft k . When the pin i^2 is released from the lever b^2 on the downward movement of the needle-bar, the spring h^4 rotates the lever h in a direction opposite to that in which it was moved by the slide-bar i . This reverse movement releases the parts of the ring g^9 from engagement with the wall of the groove g^8 and permits the said parts g^9 to slide freely in said groove. The slide-bar i is also drawn back, so that the pin i^2 will be in position to be engaged by the lever b^2 on its next throw. In order to vary the throw of the slide-bar i , said lever is provided with an upwardly-projecting arm i^3 , which contacts with the stop i^4 , set into the frame of the attachment and held from rotation by a set-screw i^5 . This stop is made in the form of a screw having its head eccentric to the body portion, so that by adjusting the same by turning in its seat the slide-bar i will be permitted to move a greater or less distance. A screw i^5 bears against the body of the eccentric-headed screw i^5 and holds it in any desired position.

The intermittent rotary motion of the shaft k is imparted to the cloth-clamp plate by the following means: The rear end of the cloth-clamp plate is provided with a vertical arm l , having a slot l^1 . To the frame projection a^3 is pivoted a lever l^2 , having a longitudinal slot l^3 , in which slot is mounted a screw-ended stud l^4 , having a collar l^5 and a jam-nut l^6 engaging the screw-threaded end of said stud and serving to clamp the same to the lever l^2 in any desired position in the slot l^3 , thereby enabling the extent of the longitudinal feed of the work-clamp plate to be varied according to the length of the buttonhole to be sewed. The stem of the stud l^4 is set into an opening in the block l^7 , which block is grooved on its sides and is sprung into the slot l^1 , so that it presents a flat bearing-surface to the walls of said slot. The block l^7 fits loosely in the slot l^1 and provides a larger wearing and bearing surface and a more durable connection than when the stud l^4 engages directly with the walls of said slot. The lever l^2 is pivotally connected at l^8 to a slotted double-rack pitman m , which is engaged by a segmental pinion m' , keyed or otherwise secured

to the shaft k , said pinion engaging with the respective racks m^2 and m^3 of the pitman m at opposite points in its rotation. The said pinion and rack are held in position with respect to each other by a washer k' and a thumb-screw k^2 , which engages with a screw-threaded seat in the end of the shaft k .

From the above description it is obvious that the cloth-clamp plate will be moved in opposite directions by the segmental pinion m' and the pitman m and that while the pinion m' turns through the idle parts of said pitman no movement will be imparted to the cloth-clamp plate. This momentary suspension of the longitudinal feed of the cloth-clamp plate occurs at the end of the sewing of a set of side or binding stitches, and at such time the cloth-clamp plate is shifted to bring the cloth-clamp f and the work into proper position for sewing the opposite side of the buttonhole. This shifting of the cloth-clamp is effected by a cam-wheel o , fixed to the shaft k by a set-screw k^3 or any other suitable means. This cam-wheel is provided with a peripheral groove having two straight sections and two cam-sections, the latter being opposite to each other and comparatively short and inclining at opposite angles to each other with respect to the axis of the cam-wheel and shaft, all as fully set forth in United States Patent No. 549,538. This cam-groove is engaged from below by a roller p^6 on a stud formed integral with a lever p' , fulcrumed on a screw-bolt p^2 , extending through an opening in the frame portion a^2 . On the lever p' and having dovetailed engagement therewith is a cross-head slide p^3 , which may be clamped to said lever in any desired position by a set-screw p^4 , which works through a longitudinal slot e^2 in the retaining-plate e . The cross-head p^3 engages the cloth-clamp plate f through shoes p^5 , these shoes being of the same construction and serving the same purposes as the shoes d^2 on the cross-head d . During the longitudinal feed of the work-clamp plate the roller p^6 will be in engagement with one of the straight portions of the groove on the cam-wheel o , and consequently the cross-head p^3 will be held stationary. Whenever the cloth-clamp plate reaches either of its limits and during the time that the segmental pinion is out of engagement with both racks of the pitman m , the roller p^6 comes into engagement with one of the cam-sections of the cam-wheel o , and the lever p' and cross-head p^3 will shift the cloth-clamp plate so as to properly position the cloth-clamp for sewing a row of stitches on the opposite side of the buttonhole. The extent of the lateral or shifting movement of the cloth-clamp plate may be varied by adjusting the cross-head p^3 along the lever p' . During this shifting movement barring stitches will be formed at the end of the buttonhole as the vibratory movement of the cloth-clamp plate continues by the operation of the cam c , as heretofore explained.

The cloth-clamp f is composed of two pieces

fastened together in any suitable manner, as by screws f^3 , the lower one of said plates being serrated, as shown. The upper one of said plates has two slotted lugs f^4 , through each of which passes a screw f^5 , having a seat in the cloth-clamp plate f' . By these means the cloth-clamp may be adjusted laterally with respect to the plate f' . To prevent the cam-wheels c and o from being turned backward by their operating-levers, a flat spring c^8 , fitting into slots cut into the body of the frame, bears frictionally against the side of said wheels and is held in such position by a set-screw tapped in a hole in the body of the frame.

The present attachment may be converted into a tacker by simply removing the cross-head p^3 or shifting it so that its axis shall be coincident with the fulcrum of the lever p' . Under such conditions the forward and backward movements of the cloth-clamp plate will be in the same line.

What we claim as our invention, and desire to secure by Letters Patent, is—

1. In a sewing-machine attachment the combination with a cloth-clamp plate, of means for imparting to said plate a vibratory movement, said means comprising a cam, a lever having a grooved pawl thereon, a screw having engagement with said lever, a washer between the screw-head and lever, and a spring clamped at one end between said screw-head and washer, and its other end resting in the groove of the pawl to hold it in engagement with said ratchet-wheel, substantially as described.

2. In a sewing-machine attachment, the combination with a cloth-clamp plate, of means for imparting to said plate a vibratory movement, said means comprising a ratchet-actuating lever, a link having two eyes, whose axes are at right angles to each other, the said link adapted to be secured to the needle-bar of the machine through one of said eyes, the other eye serving as a support for the ratchet-actuating lever, said lever resting loosely in said eye and adapted to move lengthwise or slide therein when the needle-bar is reciprocated, substantially as described.

3. In a sewing-machine attachment the combination with a slotted cloth-clamp plate, of means to impart to said plate a vibratory movement, comprising a cam, a lever engaging said cam, a cross-head on said lever, bearing-shoes conforming on their inner sides to said head and grooved on their outer sides to engage the walls of the slot of said plate, and means to impart to said plate a longitudinal movement comprising a shaft, a clutch device connected to said shaft, a slide-bar resting loosely on a flange of the attachment and adapted to intermittently engage said clutch device to rotate said shaft, a slotted arm connected to said plate, a slide-block secured in said slot, a slotted lever pivoted to the frame

of the attachment and actuated by said shaft, and a stud passing through an opening in said block and connecting said lever and arm, substantially as described.

5. In a sewing-machine attachment, the combination with a slotted cloth-clamp plate, of means to impart to said plate a vibratory movement comprising a shaft and means to rotate the same from the needle-bar of the machine, a cam secured to said shaft, a lever engaging said cam, means to impart to said plate a longitudinal movement comprising a shaft, a clutch device connected to said shaft, a slide-bar resting loosely on a flange of the attachment and adapted to intermittently engage said clutch device to rotate said shaft, a cam on said shaft to shift the cloth-clamp plate to bring the work into proper position for sewing, and a flat spring fitting into slots cut into the body of the attachment and bearing frictionally against the side of said cams, to prevent their reverse movement, substantially as described.

5. In a sewing-machine attachment the combination with a cloth-clamp plate, a shaft, mechanism actuated by said shaft for impart-

ing to said plate a longitudinal feed movement, a clutch device for imparting an intermittent rotary movement to said shaft, a slide-bar for actuating said clutch device, 30 said slide-bar resting loosely on a flange of the attachment and having an upwardly-extending arm, an adjustable stop for said slide-bar consisting of a screw seated in the arm of the attachment and having an eccentric 35 head which contacts with said upwardly-extending arm, substantially as described.

In testimony whereof we have signed our names to this specification in the presence of subscribing witnesses.
